(57) **CLAIM**

We claim the ornamental design for a dual-compartment container, as shown and described.

DESCRIPTION

FIG. 1 is a perspective view of a dual-compartment container, showing our new design in a fully closed configuration;

FIG. 2 is a top plan view thereof;

FIG. 3 is a front elevational view thereof;

FIG. 4 is a rear elevational view thereof;

FIG. 5 is a bottom plan view thereof;

FIG. 6 is a left-side elevational view thereof, the right-side elevational view being a mirror image thereof;

FIG. 7 is a cross-sectional view thereof, taken generally along lines 7-7 of FIG. 6;

FIG. 8 is a perspective view thereof, illustrated in a partially open configuration; and,

FIG. 9 is a perspective view thereof, illustrated in a fully open configuration.

The broken lines showing latches in FIGS. 1-3, 8 and 9 depict environmental matter and form no part of the claimed design.
